UNITED STATES PATENT OFFICE.

SAMUEL W. EVANS, JR., EDMUND L. GLENN, AND WILLIAM H. GASKILL, OF PHILADELPHIA, PENNSYLVANIA; SAID GLENN AND GASKILL ASSIGNORS TO SAID EVANS, JR.

POCKET-LAMP.

SPECIFICATION forming part of Letters Patent No. 432,304, dated July 15, 1890.

Application filed June 18, 1889. Serial No. 314,440. (No model.)

To all whom it may concern:

Be it known that we, SAMUEL W. EVANS, Jr., EDMUND L. GLENN, and WILLIAM H. GASKILL, citizens of the United States, residing in the city and county of Philadelphia, State of Pennsylvania, have invented a new and useful Improvement in Pocket-Lamps, which improvement is fully set forth in the following specification and accompanying drawings.

Our invention consists of novel features in a lamp employing a strip of fulminates for lighting the same, and generally known as a "pocket-lamp," as will be hereinafter fully set forth and definitely claimed.

Figure 1 represents a partial vertical section and partial side elevation of a lamp embodying our invention. Fig. 2 represents a view of the top cap thereof. Fig. 3 represents a top view of the interior of the lamp.

Fig. 4 represents a horizontal section on line *xx*, Fig. 1. Fig. 5 represents a partial vertical section and partial side elevation of the upper portion of the reservoir. Fig. 6 represents a partial vertical section and partial side elevation of a modification of the parts shown in Fig. 5. Fig. 7 represents a side elevation of a detached portion. Fig. 8 represents a bottom plan view of the part shown in Fig. 7. Fig. 9 represents a top view of the bottom bushing of the reservoir. Fig. 10 represents a perspective view of the spring which presses the fulminates against the striking device. Fig. 11 represents a perspective view of the easing on a reduced scale. Fig. 12 represents

a perspective view of the easing and top cap on an enlarged scale. Fig. 13 represents a section of a portion of a modification.

Similar letters of reference indicate corresponding parts in the several figures.

Referring to the drawings, A designates the reservoir of a lamp known as a "pocket-lamp," the upper portion of which is drawn, spun, stamped, or struck up with spiral crimping, corrugations, or threads B, which are adapted to engage with the pellet C of the strip or tape D, said pellets being formed of fulminate, and said tape being fitted in a vertical pocket E at the side of the casing E', which incloses the reservoir A. Rising from and secured to the pocket E is a spring F,

which bears against the tape D, so as to press the latter against the threads B, and also hold said tape while the pellets or fulminates are engaged by the striking-finger G, which is preferably formed of wire and radiating from the top of the reservoir A, it being seen that said wire is coiled through an eye H on the reservoir, thus providing a spring for the finger, and also connected with an eye H', also on the reservoir, whereby said finger is properly held in position. The top of the reservoir is stamped or struck up with the threaded portion B, having a burner or wick-tube J, and the eyes H H' integral with said top.

In Fig. 6 we show the threaded portion B of the reservoir made separate from the body of the reservoir and adapted to be fitted thereover, the object in this case, as well as in the construction shown in Fig. 5, being to avoid cut screw-threads, which weaken the wall of the reservoir, the latter being of light metal or material. Within the reservoir at the bottom thereof is a threaded bushing K, which is firmly held in position, and to the same is fitted a threaded plug L, the base whereof has a milled rim M, whereby said cap may be screwed and unscrewed, it being seen that when the plug is screwed into position the further rotation of the same causes the rotation of the reservoir, whereby the strip D is raised and the fulminates are successively presented to the finger G, and thus ignited, the flame flashing toward the wick of the lamp and igniting the same.

Interposed between the reservoir A and the outer casing E' is a bushing N, which tightly hugs said casing, so as to be prevented from rotation, it being seen that the strip D is outside of said bushing, so that as the reservoir A rotates within said bushing it is prevented from coming in contact with the said strip or the fulminates thereof.

It will be seen that when the reservoir is rotated the strip is raised, as has been stated. When the bottom of the thread of the portion B reaches a fulminate, it is intended that it shall engage under the same, so as to prevent crushing of the fulminate or premature discharge of the same. To accomplish this the lower edge of the threaded portion B of the

reservoir has a recess P, into which the fulminates successively enter, and are thus removed from the path of the sharp edge of the bottom coil of the threaded portion, the upper 5 wall of said coil, however, being in position to ride properly under the fulminates, and thus raise the same with the strip. As there is lateral pressure on the tape or fulminates, owing to the rotation of the portion B of the 10 reservoir, and a consequent tendency of said tape to displacement, the sides of the spring are formed with guides G, which project inwardly from said spring, so as to enter the pocket E and embrace the sides of the tape.

15 R designates the cap of the lamp, the same being shown closed in Fig. 12 and open in Fig. 1, and being hinged to the outer casing E', the side opposite to the hinge having a snap or catch S for holding the cover in closed position. The hinge of the cap, Fig. 12, consists of a staple-shaped piece T of wire, which is mounted in the ear U on said cap, and having its legs entering ears V on the side of the casing and soldered or otherwise fastened thereto.

20 The reservoir A may be supplied with oil at the bottom thereof through the opening occupied by the plug.

25 In Fig. 13 we show a portion of a beaded rim employed in lieu of the milled rim, Figs. 1 and 4.

30 The casing E', pocket E, ear V for the hinge of the cap, and the eye W, which receives the lower end of the spring F, are formed in one 35 piece of metal suitably drawn, as will be seen in Fig. 11.

The bushing K and plug L have their threads formed by rolling or spinning, said bushing and plug being constructed of sheet metal.

40 Having thus described our invention, what we claim as new, and desire to secure by Letters Patent, is—

45 1. In a pocket-lamp, a casing with a rotatable reservoir therein, having a removable cap with a wick-tube, eyes H H' and the screw-threads B, said tube, eyes, and threads being stamped or struck up and integral with said reservoir, a strip of fulminates, a finger for holding said strip of fulminates relatively to

the screw-threads of the reservoir, and a striking-finger, said parts being combined substantially as described. 50

2. A lamp having a strip of fulminates, in combination with a striking-finger, which is connected with the top of the lamp and provided with a coil around the attaching-eye on said top, substantially as described. 55

3. A casing having a pocket with a strip of fulminates therein, in combination with a rotatable lamp, and a stationary bushing interposed between said casing and lamp, substantially as described. 60

4. A lamp having a reservoir with a removable top portion provided with a wick-tube and the eyes H H', a wire passing through 65 said eyes and forming a striking-finger, and a strip of fulminates adapted to be brought into contact with said finger, said parts being combined substantially as described.

5. A lamp consisting of a reservoir with 70 wick-tube J and threaded portion B and provided at its lower end with a threaded bushing, a threaded plug in said bushing and having a projecting rim, an outer casing with vertical 75 pocket, a bushing between the reservoir and casing and closely fitted to said casing, a strip of fulminates in said pocket, a striking-finger secured to the top of the reservoir, and a spring bearing against said strip, said parts being combined substantially as described. 80

6. A lamp consisting of a rotatable reservoir having a threaded portion with recess P in its lower edge, with a striking-finger secured in ears on the top thereof, an outer casing with vertical pocket, a strip of fulminates in said pocket, and a spring secured to said casing adjacent to the pocket therein, being projected upward to form a bearing against said strip and having side projections forming guards for said strip, said parts being combined substantially as described. 85
